UNITED STATES PATENT OFFICE.

RALPH D. STEVENSON, OF HUBBARD, OHIO.

MAGAZINE PENCIL.

Application filed August 2, 1923. Serial No. 655,283.

The present invention relates to a pencil construction of the type in which leads may be contained within the pencil in a magazine within the pencil, and individual leads maintained at the point of the pencil in a predetermined position and fed outwardly as the individual lead is used and worn down.

The object of the invention is to provide a pencil of the type mentioned, which is simple in construction and composed of few parts which may be economically manufactured at low cost.

Reference should be had to the accompanying drawings forming a part of this specification, in which Fig. 1 is a sectional elevation of the pencil; Fig. 2 is an elevation with portions in section showing parts of the pencil in disassociated relation; Fig. 3 is a top plan view of a retaining member; Fig. 4 is an elevation of a portion of the pencil; Fig. 5 is an elevation of another portion of the pencil.

Referring to the drawings, 1 indicates the barrel of the pencil which at its upper end is open ended and at its lower end is provided with a portion of less diameter, as indicated at 2, and providing a shoulder 3. The lower end of the part, which is of reduced diameter, has inwardly slanting sides, as indicated at 4, and there is a reentrant slot 5 at the end of the tapered portion 4.

Co-operating with the lower portion of the barrel 1 is a conically shaped head 6, which head at its upper end is provided with straight cylindrical wall portion indicated at 7.

When the member 6 is assembled with respect to barrel 1 upon the lower end thereof, as indicated in Fig. 1, the cylindrical portion 7 abuts against the shoulder 3, and the angle of the tapered portion 4 corresponds with the taper on the inside wall of the member 6.

Within the member 6 there is an annular ridge 8 which may be formed directly in the metal itself, as is indicated in the drawing, or any other means may be utilized to provide the equivalent of this ridge 8.

Upon the inner wall of the member 6 and just above the ridge 8 there is a short member 9 which is either affixed to the inner wall of the member 6 or formed as a part thereof, this member 9 being adapted to extend into the reentrant slot 5 when the member 6 is assembled with respect to the barrel 1, thereby preventing relative rotation between the

head 6 and the barrel 1, but permitting longitudinal or axial movement.

Within the member 6 there is a part generally indicated at 10, which is provided with an axial opening indicated at 11 in Fig. 1. The upper end of this member is threaded, as indicated at 12, and the portion which lies below the threaded part just indicated is split so as to form two parts 13 and 13^a. At the lower end of the member 12 there is a conically shaped head 14 which at its base is of slightly greater diameter than the split portions 13 and 13^a, thereby forming a shoulder 15. The angle of taper of the portion 14 corresponds with the angle of the inside wall of the member 6.

The splitting of the member 10 into the parts 13 and 13^a is carried through the conical portion 14, and the two parts of the conical member 14 may be correctly described as gripping jaws. The inherent resiliency of the metal, particularly the metal contained in the parts 13 and 13^a, will normally hold the gripping jaws apart, and when the conical portion or the gripping jaw portions are moved toward each other, and subsequently released, the resilience of the metal will move the gripping jaws apart.

Within the barrel member 1, at the lower portion thereof and co-operating with the slanting wall portion 4, is a member 17 having a portion of its outside wall made slanting, as indicated at 16, and at the upper portion of this member the outside surface is cylindrical, as indicated at 17^a. This member when assembled within the barrel 1 has its lower tapered portion 16 co-operating with the tapered portion 4, and its cylindrical portion co-operating with the cylindrical portion of the barrel member 1 which is just above the tapered portion 4.

This member 17 has a snug fit within the barrel member so that when the two are assembled they are held together by the friction engendered by the engagement of the adjacent walls.

The member 17 is provided with a threaded opening which is adapted to receive the threaded end 12 of the member 10, and this opening at its upper end is made flaring, as indicated at 18, so as to provide an efficient means for guiding leads which may be contained within the barrel 1 into the channel 11 of the member 10.

When the parts which have been described are in their assembled relationship, the mem-

ber 10 has its threaded end 12 screwed into the threaded portion of the member 17, and the member 10 is assembled within the conical head portion 6 with the conical portion 14 of the member 10 in engagement with the inner walls of the member 6 adjacent the end thereof.

The head member 6 at its lower end is provided with a straight opening 6^a which 10 is in line with the opening through the member 10, as clearly shown in Fig. 1.

There is a retaining member 19 which is more clearly indicated in Fig. 3, which is 15 preferably made of sheet metal, and preferably slightly dished, the metal having sufficient resiliency so that in assembling the member 19 within the head member 6 this member 19 may be snapped past the ridge 8 with its peripheral edge in engagement with 20 the lower portion of the ridge. The natural expansive tendency of the member 19, taking into consideration the fact that the portion of the member 6 below it is of reduced diameter, causes the edge of this member 19 to wedge 25 tightly and firmly against the under side of the ridge 8.

The member 19 is provided with a central opening 19^a which is of slightly greater diameter than the member 10, so that the member 10 may freely pass through the opening in this member 19.

The particular form of the member 19 which is shown in Fig. 3 is not essential, but this form does give the required resiliency 35 of the metal, which is necessary in order to snap it beyond the ridge 8 in assembling the parts of the pencil.

Below the member 19 there is a spring 20, which spring at one end bears against the 40 under side of the member 19 and at its opposite end bears against the shoulder 15 of the member 10, so that the function of the spring 20 is to urge the member 19 upwardly, and inasmuch as the member 19 is pressing 45 against the ridge 8 which forms a part of the head 6, the spring 20 may be said to continuously urge the head member 6 of the pencil into position with respect to the barrel 1 in which it is shown in Fig. 1, that is 50 to say, with the end of the head member 6 in engagement with the shoulder 3 at the lower portion of the barrel 1.

When the head member 6 is urged to its uppermost position, as has just been described, the conical portions 14 of the member 10, which in effect form gripping jaws, are urged toward each other, and so will firmly grip a lead which may be in position 55 in the channel 11 which is formed in the member 10.

When it is desired to feed the lead further forward, or to push the lead back, so that the point is wholly within the head member 6 of the pencil, the member 6 may be gripped by the fingers and pulled a slight

distance away from the barrel 1, which would serve to release the pressure on the members 14 and so release the grip on the lead which is within the channel 11, so that the leads may move outwardly under the action of gravity, or it may be pushed up so as to protect the point of the lead.

At the opposite end of the barrel member 1 there is an inserted member 21. This member has a cylindrical portion 22 which is 75 adapted to snugly engage with the inside wall of the barrel 1 at the outer end of the barrel. This engagement, however, is not so tight that it can not be removed, but is sufficiently tight so that the member 21 is retained when it is inserted in the end of the barrel 1. Above the portion 22 which has been described there is a part of slightly greater diameter, as indicated at 23, thereby forming a shoulder 24 which is adapted to 80 engage with the end of the barrel 1, so as to limit the inward movement of the member 21. This member 21 is hollow and receives an eraser member 25, which may be made of rubber or such erasive material as may be desired 90 There is also a cap 26 which is formed with a cylindrical body portion adjacent one end thereof, which is adapted to engage with the outside surface of the portion 23 of the member 21, this engagement being a frictional engagement in which there is a snug fit in engagement so as to prevent accidental displacement of the parts, but not sufficiently great to prevent their being separated when such is desired.

The cap may be provided with a beaded part 27 which fits over the end of the barrel member 1, obviating any sharp edges and giving a finished appearance.

The portion of the cap above the cylindrical part 26 may be given any desired form, the only requirement being that there should be sufficient room to receive the end of the eraser member 25.

At the upper end of the cap member 26 there may be provided an arrangement whereby a lead may be pointed, and in the present instance the construction provides a plate 28 which is secured to the cap 26 by providing an annular recess 29 in the wall 115 of the cap and crimping the metal in the edge of the cap around the edge of the member 28. The member 28 is provided with a conical recess 30 which may be formed to provide an abrading surface of any description so that when the point of a lead is presented to the abrading surface, and a turning action given to the lead, it will cause the end of the lead to become pointed.

Inasmuch as the cap 26 is removable, a lead 125 which is contained within the gripping jaws 14 at the end of the pencil may be sharpened without removing the lead, but rather removing the cap and inserting the end of the lead into the conical sharpening member 30. 130

The space within the barrel member 1 may conveniently serve as a reservoir for containing leads, and these leads may be inserted by removing the cap 26 and the member 21.

Leads which are contained within the barrel member 1 will be automatically fed into the channel 11 on the member 10 because the pencil, which is usually carried in vertical position, will cause the leads to move toward the lower end of the barrel portion and be in contact with the upper part of the member 17. The ends of the lead will engage with the conical surface 18, and so be guided toward the channel 11. The channel is of such size that it can not receive more than one lead, so that there will be no jamming at this point.

It will, of course, be obvious that if it be desired a lead may be inserted through the opening 6^a in the head member 6 of the pencil by moving the head member 6 against the action of spring 12 so as to open the jaws 14.

Having described my invention, I claim:—

1. A pencil comprising a barrel portion, a head portion which is longitudinally movable with respect to the barrel portion, gripping jaws within the head portion said gripping jaws being stationary longitudinally with respect to the head portion and adapted to grip the leads, and means for guiding a lead from within the barrel portion between the said gripping jaws.

2. A pencil comprising a barrel portion, a head portion which is longitudinally movable with respect to the barrel portion, resilient means normally holding the movable head in position upon the barrel portion, gripping jaws within the head portion, said gripping jaws being stationary longitudinally with respect to the head portion and adapted to grip the leads, and means for guiding a lead from within the barrel portion between the said gripping jaws.

3. A pencil comprising a barrel portion, a head portion which is mounted at the end of the barrel portion and slidable thereon, resilient means normally holding the head portion upon the barrel portion, gripping jaws within the head portion, said gripping jaws being stationary longitudinally with respect to the head portion and adapted to grip the leads, and means for guiding a lead from within the barrel portion between the said gripping jaws.

4. A pencil comprising a barrel portion, a head portion which is mounted upon the barrel portion and longitudinally movable with respect thereto, detachable gripping jaws within the head portion and adapted to grip the leads, and means for supporting said gripping jaws by the barrel portion.

5. A pencil comprising a barrel portion, a head portion which is mounted upon the

body portion and longitudinally movable with respect thereto, a resilient member normally holding the head portion in position upon the barrel member, and gripping jaws within the head portion adapted to be engaged by the head portion to move them to gripping position.

6. A pencil comprising a barrel portion, a head portion mounted upon said barrel portion, which head portion is longitudinally movable with respect to the barrel portion, a resilient means normally holding the head portion to the barrel portion, and gripping jaws mounted within the head portion and detachably supported from the barrel portion, said gripping jaws being engaged by the head and moved to gripping position when the head is in its innermost position.

7. A pencil comprising a barrel portion, a head portion mounted upon the barrel portion at the end thereof and longitudinally movable with respect to the barrel portion, means for preventing relative rotation between the head portion and the barrel portion, and gripping jaws within the head portion for gripping the leads, removably carried by the barrel portion, said gripping jaws being adapted to co-operate with the movable head to move the jaws to gripping engagement when the head is in its engaged position on the body portion.

8. A pencil comprising a barrel portion, a conically shaped head portion longitudinally movable with respect to the barrel portion, lead gripping jaws within the head portion, said gripping jaws being supported by the barrel portion, said jaws being in position to be engaged by the inner face of the head portion to be moved into gripping position.

9. A pencil comprising a barrel portion, a conically-shaped head portion which is mounted and longitudinally slidable on the barrel portion, resilient means normally holding the head portion and the barrel portion to each other, and gripping jaws within the head portion supported from the barrel portion, said gripping jaws being adapted to be engaged by the movable head to grip the leads.

10. A pencil comprising a barrel portion, a conically shaped head portion which is mounted upon and longitudinally movable with respect to the barrel portion, a lead gripping member mounted within the head portion, means for supporting said member from the barrel portion, said member having an axial channel formed therein and at its end portion being formed to provide two oppositely disposed jaws, the said jaws being moved to engaging position by the movable head portion.

11. A pencil comprising a barrel portion having one end open, a head member cooper-

ating with the open end of said barrel portion and mounted to be longitudinally movable thereon, a resilient member normally holding said head and barrel portion in engaging position, a supporting member located within said barrel portion at the open end thereof, a lead gripping member carried by said supporting member and provided with oppositely disposed jaws, said lead gripping member being positioned within said head member and engaged thereby to move said jaws into gripping position.

12. A pencil comprising a barrel portion, a head member slidably mounted at the end

of said barrel portion, a lead gripping member supported by said barrel portion and having an axial opening therethrough, said gripping member having its free end split through a portion of its length to provide conically shaped jaws adapted to be engaged by said head member, a retaining member mounted inside said head member, and a spring engaging said retaining member and said gripping member for normally holding said jaws in lead engaging position.

In testimony whereof, I hereunto affix my signature.

RALPH D. STEVENSON.
